UNITED STATES PATENT OFFICE.

FREDERICK J. REICHLE, OF ST. PAUL, MINNESOTA, ASSIGNOR TO BROWN & BIGELOW,
OF ST. PAUL, MINNESOTA, A CORPORATION OF MINNESOTA.

LETTER CASE AND WALLET.

Application filed November 12, 1924. Serial No. 749,416.

To all whom it may concern:

Be it known that I, FREDERICK J. REICHLE, a citizen of the United States, residing at St. Paul, in the county of Ramsey 5 and State of Minnesota, have invented new and useful Improvements in Letter Cases and Wallets, of which the following is a specification.

My invention relates to letter cases and 10 wallets wherein compartments are arranged in an accessible position relative to the use of a billfold so that it can be carried in the coat pocket to take the place of a wallet to hold bills, letters and cards which are 15 easily accessible when desired.

A feature of my invention is in providing 20 a case made of leather or other suitable material so as to provide an attractive wallet like holder of a simple construction and having the compartments of the same arranged in co-relation with each other so as to give access to letters on one side of the case, bills on the other side of the case and calling or business cards held separately 25 in a compartment associated with the letter holding compartment and accessible without disturbing the letters in the letter compartment.

It is desirable to provide a wallet case 30 wherein letters, cards, and bills may be carried, each in a flat state without folding and while cases have been made before for letters, also for bills, they have been each separate wallet members and have not 35 included a simple construction where the two are arranged together and provided with a card compartment as I have designed and arranged in my wallet case.

These features together with the simplicity of construction and arrangement of 40 the parts will be more clearly and fully set forth in the specification and claims.

In the drawings forming a part of these 45 specifications:

Figure 1 is a perspective view of the inside of my letter case and wallet.

Figure 2 is a section on the line 2—2 of 50 Figure 1.

Figure 3 is a section on the line 3—3 of Figure 1.

Figure 4 is a detail portion of my letter case and wallet illustrating an alternative formation thereof.

The drawings illustrate my case or wallet 55 A, which is formed of leather in the ordi-

nary, well-known manner, having its outer face formed of an art or mission leather finish while the inner flap and parts are formed of leather or other material suitably blended in color and finish to match the outer finish of the wallet case, all of ordinary construction and not shown in detail in the drawings because it is obvious that detail of construction as to the filling or stiffening material within the case or wallet 60 can be eliminated in relation to the material used as the covering, by reason of the fact that different thicknesses of leather can be readily adapted to make up my case. Where my case is made of heavy leather it 70 is not necessary that it have any stiffening or filler within the same and in fact it does not even need a lining to make up the necessary body to the side walls. All of this construction is of ordinary, well-known detail and this is not illustrated or pointed out in the drawings.

My case A is provided with side walls 10 and 11 which are formed from the same piece of material and folded together along 80 the central portion of line 12 so that the walls 10 and 11 fold together and are of approximately uniform size.

When folded the case A forms a rectangular wallet case which is of a size 85 adapted to fit within the inside coat pocket conveniently in a manner to hold letters, bills and cards protected within the case, but very accessible.

The side wall 10 is provided with an integral flap 13 which is folded along the edge 14 and is stitched at 15 along the bottom edge 16 of the case A. The flap 13 folds over onto the inside of the wall 10 and is provided with an angularly disposed 90 downwardly inclined edge 17 which provides a cut-away portion to the flap 13 so that letters held within the compartment 18, formed by the flap 13 folding onto the side 10, permits the letters to be easily 100 turned over at the corner, when the upper free corner 19 of the flap 13 is folded back so that any letter can be removed individually from the compartment 18. The stitching of the wall 10 and the flap 13 at the line 15 closes the same so that the case is closed at the end 16 of the same and holds the letters from slipping out from this end of the compartment.

Within the compartment 18 is provided a 110

small card receiving compartment 20 which is provided with a flap having a downwardly inclined angularly disposed edge 21 so that the cards within the compartment 20 can be readily engaged on the corner when the letters are folded back slightly in opening the case A. In this manner business or calling cards can be held within the compartment 20 in conjunction with the letter compartment and without adding any complicated arrangement of parts, but rather providing a simple construction for the letter and card compartments which are compactly arranged together to take up a small amount of space.

Within the wall 11 is provided a compartment 22 for paper bills, by stitching the flap 23 at 24 along the bottom 16 and at 25 along the longitudinal edge 26 of the wall 11. In this manner the flap 23 is provided with a free upper corner 27 which can be folded back as illustrated in Figure 1 to give free access to the bills within the compartment 22.

The flap 23 is shorter in length than the wall 11 so that the upper edge 28 of the same is spaced from the upper edge 29 of the case or wallet A, and stitched to the end 29 at 30 is a second flap 31 to form a cover flap over the edge 28 and corner 27 of the flap 23.

The flap 31 is provided with angularly extending and downwardly depending edges 32 and 33 which come together to form a depending pointed portion 34 extending below the side edges 35 of the flap 31. This pointed portion 34 forms a protruding portion which has a tendency to lock the free edge 28 beneath the flap 31 and to provide a shoulder at 34 which can be engaged by the thumb or finger to raise the flap 31 slightly. The inclined faces 32 and 33 engage against the edge 28 of the flap 23 when the flap 23 is turned back as illustrated in Figure 1 to remove the corner 27 from beneath the flap 31 and the angular inclination of the sides 32 and 33 together with the shoulder at 34 having a tendency to resist the opening of the flap 23.

The shortness of the flap 31 increases the resistance of the same against the edge 28 to hold the same under this flap 31 and the inclined edge 33 permits the flap 23 to be partially opened up at the shoulder or pointed end 34 so that paper bills can be removed from the compartment 22 without opening this compartment to the extent of removing the corner 27 as illustrated in Figure 1. When the compartment 22 is opened in this manner the flap 31 bears against the edge 28 to cause the same to be readily moved into closed position by any slight pressure on the flap 31 to overcome the frictional engagement by the edges 28 and 33. Moreover the edge 33 has a tendency to force against the edge 28 to form a cam action which is inclined to move the flap 23 into closed position.

The short length of the flap 31 together with the angularly disposed edges 32 and 33 form an important feature of my case and provides a very effective compartment for holding bills in conjunction with the other compartments 18 and 20 for letters and cards respectively so that the user of my case can have all of these advantages in carrying my wallet case.

It is essential to provide a leather case which is wear resisting and made up of mission or art leather so as to provide an attractive holder for letters, cards and bills. Business men desire to have their letters of importance, business cards, and bills in readiness for use at any time and yet held together in one case so that they can be removed from the pocket collectively and held accessible for immediate use from any of the compartments. This is accomplished in my case and thus I have provided a holder for letters, cards and bills which business men greatly appreciate.

In accordance with the patent statutes I have described the principles of operation of my letter case and wallet, and while the drawings illustrate a particular formation of the same, I desire to have it understood that these are only illustrative and that the invention can be carried out by other means and applied to uses other than those above set forth or within the scope of the following claims.

I claim:

1. A letter case and wallet including a body portion adapted to form two uniform side walls connected together in a manner to fold onto each other, a letter compartment within one wall, a bill compartment within the other of said walls, and a card compartment attached to the inner wall of said letter compartment.

2. A letter case and wallet comprising side walls of a uniform size adapted to fold onto each other, a flap formed integral with the side walls and folded in a manner to extend over the inside of one of said walls and stitched along one end of said wallet to form a letter compartment within one of said side walls, a flap secured to the inner side of the other side wall stitched along the bottom and longitudinal side of said wallet, having one end thereof spaced away from the end of the wallet and a short flap adapted to cover the space on the inside of the wallet, from which the end of said second flap is spaced, in a manner to overlap the spaced end to form a bill compartment closed at one end and accessible at the other end by raising the short flap by engagement with the end of the flap covered by said short flap.

3. A letter case and wallet including a pair of side walls having a uniform size and adapted to fold onto each other, one end of

- 5 said wallet forming the bottom and the other end forming the top, flaps extending over the inside of said side walls and closed along the bottom and longitudinal side edges of
 10 said wallet to form two adjacent compartments with the adjacent inner edges of the flaps spaced from each other and free to be turned back to open the compartments along the inner and upper edges of said compartments respectively, a short flap secured along the upper edge of one of said side walls to cover the flap secured on that side of the wallet, adapted to form a guard for the upper end of that compartment whereby
 15 the bills may be concealed within that compartment and a card case compartment concealed within said other compartment on the wall adjacent the bill compartment.
4. A wallet including a book fold formation, a letter case compartment on one side of said wallet, a bill compartment on the other side of said wallet and a card case compartment within and concealed by said letter case compartment.
- 20 5. A letter case and wallet comprising a body portion adapted to be folded to form two side walls of uniform size, a portion integral with one of said sides folded to form a flap on the inside thereof to provide a letter pocket, a card pocket concealed within said letter pocket and a pair of flaps secured to the side opposite said letter pocket adapted to fold over each other in a manner to form a pocket adapted to conceal bills within the same.
- 25 6. A letter case and wallet including a pair of side walls of uniform size adapted to fold onto each other, a flap formed integral with one of said side walls folded over onto the inside of said side wall and stitched along the end thereof to form a letter compartment, the end opposite said stitched end of said flap extending at an inwardly inclined angle toward the stitched end to provide an open corner on the inside of said letter compartment, a card pocket concealed beneath said letter compartment flap and having the open end thereof inclined with the same angular position that said letter compartment flap has, a pair of flaps secured to the side wall adjacent said letter compartment, one of said flaps having a rectangular formation and stitched along two sides thereof to the bottom and outer longitudinal edge of said wallet and the other flap stitched along the upper edge of the side wall and having the free inner edge thereof formed with angularly disposed portions extending inwardly to form a pointed end at the juncture of said inclined edges and adapted to overlap the free end of the other flap in a manner to form a bill compartment which is adapted to conceal bills within the same, which when opened permits the free end of the bill flap to engage with the angularly disposed edges of the flap secured at the upper end of said wallet.
- 30 7. A letter case and wallet including uniform side walls adapted to fold onto each other, a letter pocket formed on the inside of one of said walls and a bill receiving pocket formed on the inside of the other of said walls, a pair of overlapping flaps adapted to close the bill compartment to conceal the bills therein, and a card pocket concealed within said letter pocket, each of said pockets having the free open edges thereof positioned at the center of said wallet adjacent each other.
- 35 8. A pocket piece including a letter compartment, a bill compartment oppositely disposed to the letter compartment, locking flap for the free edge of the bill compartment said flap being formed with a depending shoulder like portion which is adapted to depend over the free edge of the flap of the bill compartment to hold the same in closed position.
- 40 9. A wallet including two oppositely disposed compartments and a card compartment secured to the back wall of one of said compartments within the same in a manner to conceal the card compartment back of the articles carried in the compartment in which the card compartment is placed.
- 45 10. A pocket wallet including a pair of compartments having closure flaps with freely disposed corners, a cover flap adapted to extend over the free edge of one of said compartments, said cover flap being formed with inclined faces oppositely disposed forming a depending shoulder extending over the free edge of the flap covered thereby to form a locking means for holding the free edge of the flap in open or closed position.

FREDERICK J. REICHLE.
